PAIR OF EYE PROTECTIVE SPECTACLES

Walter O. Parker, Henrietta, N.Y., assignor to Bausch & Lomb Incorporated, Rochester, N.Y., a corporation of New York

Filed Jan. 3, 1967, Ser. No. 5,287

Term of patent 14 years

(Cl. D57—1)

FIG. 1 is a front view of a pair of eye protective spectacles showing my new design;

FIG. 2 is a rear view thereof;

FIG. 3 is a top view thereof; and

FIG. 4 is a side view of said spectacles taken from the left side as viewed in FIG. 1, the side not shown being of substantially the same appearance as the side shown.

The dominant features of my design for the eye protective spectacles disclosed reside in the portions shown in full lines, being characterized by the tapered top center portions of the frame front adjacent the bridge, in association with the remaining features as shown.

I claim:

The ornamental design for a pair of eye protective spectacles, substantially as shown and described.
